UNITED STATES PATENT OFFICE.

HENRY C. STEEL, OF NASHVILLE, TENNESSEE.

DESIGN FOR A SADDLETREE-HORN.

SPECIFICATION forming part of Design No. 34,448, dated April 30, 1901.

Application filed February 15, 1901. Serial No. 47,516. Term of patent 14 years.

To all whom it may concern:

Be it known that I, HENRY C. STEEL, a citizen of the United States, and a resident of Nashville, in the county of Davidson and State of Tennessee, have invented and produced a new and original Design for a Saddletree - Horn, of which the following is a specification, reference being had to the accompanying drawings, forming part thereof, in which—

Figure 1 is a perspective view of a saddletree-horn embodying my design, and Fig. 2 is a side view thereof.

The design consists of the horn *a*, having the forwardly - projecting member *b* at its base, the fork *c* extending downward from the rear portion of the horn *a* at an angle to the

lower face of the forwardly-projecting member *b*, the members of the said fork *c* having the diagonally - disposed lower inner edges 20 and the rearwardly-extending curved lips or projections *d* at the lower part of said edges.

Having thus described my invention, what I claim as new, and desire to secure by Letters Patent, is—

The design for a saddletree-horn, as shown and described.

In testimony whereof I have signed my name to this specification in the presence of two subscribing witnesses.

HENRY C. STEEL.

Witnesses:

JOHN WOLTERMAN,
FORRIST WILLIAMS.
